UNITED STATES PATENT OFFICE

FREDERIC C. WINKLER, OF LAKEWOOD, OHIO, ASSIGNOR TO WESTINGHOUSE ELECTRIC & MANUFACTURING COMPANY, A CORPORATION OF PENNSYLVANIA

LIGHTING APPARATUS

Application filed December 3, 1930. Serial No. 499,706.

My invention relates to lighting apparatus and particularly to hangers for interior lighting purposes.

It is desirable to have a hanger for a globe 5 of such character that the globe may be easily taken off and cleaned and such that one person may perform all the operations.

An object of my invention, therefore, is to provide a hanger for interior lighting in 10 which the globe may be removed by holding it with one hand and releasing it from the hanger with the other, by turning the locking portion of the hanger a short distance.

Another object of my invention is to provide 15 a holder that shall be adaptable to several different thicknesses of globes without increasing the number of parts and without increasing the cost of manufacture.

A further object of my invention is to provide 20 a two-point hanger having a strap provided with relatively long arms for holding the globe so that the resiliency of the arms will make breaking of the globe less likely in case of a blow or excessive vibration.

Another object of my invention is to provide 25 a hanger of such construction that the incandescent lamp will set sufficiently forward in the holder to give the greatest amount of illumination.

A still further object of my invention is to provide 30 a holder which may be easily detached from a wall in order that repairs may be made to the socket and the electrical connections.

Other objects and advantages of the invention 35 will be readily apparent from the following description and the accompanying drawing in which

Figure 1 is a side view, partly in section, 40 of the top part of the holder,

Fig. 2 is a front elevational view of the bottom cylindrical part of the holder,

Fig. 3 is a perspective view of the metal 45 stamping which is fastened to the ceiling,

Fig. 4 is a perspective view of the metal stamping which holds the strap and socket rigidly to the top of the unit,

Fig. 5 is a perspective view of the spring- 50 metal strap for holding the globe, and

Fig. 6 is a perspective view of the assembled holder.

According to my invention, the lighting unit comprises two cylindrical pieces of sheet metal, the lower or movable portion sliding 55 into the upper or fixed portion and being adapted to be turned and held in place by a pin-and-slot connection of the bayonet type. The U-shaped two-prong strap for holding the globe is fastened rigidly at right angles 60 to a set of flanges provided in a supporting means that is rigidly fastened to the upper sheet-metal cylinder. The lamp socket is held by the same supporting means, but lower 65 in the unit, by a separate set of flanges.

A bayonet slide, designed to allow for different thicknesses of glass, is placed on the lower sheet-metal cylinder. Bayonet pins are provided in the walls of the upper casing and, when the slidable portion of the unit is 70 raised, the globe may be detached from the strap by tilting it, the globe being locked in the unit when the movable sheet-metal cylinder is lowered and the bayonet pins are turned in the slots.

Referring specifically to the drawing, 1 designates a cylindrical sheet-metal casing having a flange 2 at the top which is provided with two holes 3. A metal bar or strip 4 is fastened to the ceiling by screws or other 75 suitable means which project through slots 5 therein. Screws 6 project through holes 7 in the metal bar or strip 4 and the holes 3 in the flange 2. Nuts 8 cooperate with the screws 6 to hold the unit to the bar 4, and the screws 80 6 also project through the holes 9 and 10 in flanged metal stampings 11 and 12 which are thus fastened to the casing 1.

A U-shaped strap 13, having outwardly flanged ends 26, is attached to lips 16 and 17, 85 provided on the stampings 11 and 12, by means of screws 14 which project through holes 15 in the strap 13, and holes 16' and 17' in the lips 16 and 17, respectively.

The socket 18 is fastened to the metal 90 stampings 11 and 12 by screws 19 and 20 which project through holes 21' and 22' formed in flanges 21 and 22, of the stampings 11 and 12, and holes 23 and 24 in the socket 18. It will be noted that the flanges 21 and 22, 95

provided for holding the socket, are spaced below the lips 16 and 17 in order that the incandescent filament of the lamp may not be hidden by the casing and, at the same time, 5 permit the strap 13 to be relatively long. The hole 25 in the flange 22 of stamping 12 may be used for a large socket, a corresponding hole 25' in flange 21 of stamping 11 being provided.

10 A cylindrical sheet-metal member 27 fits inside the cylindrical sheet-metal casing 1. A plurality of sets of bayonet slots, one of which is shown at 28, are engaged by bayonet pins 29. Any desired number of sets of bayonet pins and slots may be provided in spaced relation around the walls of the respective cylinders. Each of the bayonet slots comprises a vertical portion 30, a horizontal portion 31 and an inclined portion 32.

15 The bottom cylinder 27 is shown in normal position in Fig. 6, in which the pins 29 are in the inclined slot portions 32, and the globe 34 is clamped between the flanges 26 and the beaded portion 33 of the cylinder 27.

20 If it is desired to remove the globe, the bottom cylinder 27 is turned until the bayonet pins 29 enter the vertical slot portions 30 and it is then pushed up into the casing 1 until the bayonet pins are in horizontal alignment 25 with the slot portions 31. The cylinder may then be turned until the pins 29 enter the slot portions 31. The globe 34 may then be removed without holding the cylinder 27 up by hand.

25 It may be seen from the foregoing description that my invention provides a hanger of simple and sturdy construction which may be cheaply manufactured and which may be operated easily for changing lamps and 30 cleaning globes. It will also be seen that, because of the strap construction and placement, a spring effect is obtained which acts as a shock absorber for the globe, and that this result is accomplished with maximum 35 efficiency from the source of light by placing the socket near the bottom of the unit, so that no part of the incandescent filament of the lamp will be hidden by the casing.

40 Although I have shown and described specific embodiments of my invention, it will be understood that modifications may be made by those skilled in the art without departing from the spirit and scope of the appended 45 claims.

50 I claim as my invention:

55 1. In a lighting fixture, the combination of two cylindrical shells slidably mounted one within the other, a flanged supporting member attached to one of said cylindrical 60 shells, a metal globe-supporting yoke fastened to one flange of said member, and an electrical socket attached to another lower flange of said member.

65 2. In a lighting fixture, a yoke consisting of a single piece of material having its ends

turned outward and adapted to support a globe, two cylindrical shells one of which is slidably mounted on the other, an electrical socket, and a plurality of flanged supporting members attached to the fixed shell, said 70 yoke and electrical socket being attached to separate flanges of said supporting member.

75 3. In a lighting fixture, the combination of a yoke consisting of a single piece of material having its ends turned outward and adapted to support a globe, two cylindrical shells, one of which is slidably mounted on the other, an electrical socket, and a plurality of flanged supporting members attached to the fixed shell, said yoke and electrical 80 socket being attached to separate flanges of said supporting member, one of said cylindrical shells being provided with a plurality of bayonet pins and the other shell being provided with slots adapted to engage the 85 bayonet pins and also adapted to permit adjustment and clamping of the movable shell.

90 4. In a lighting fixture, the combination of a yoke consisting of a single piece of material having its ends turned outward and adapted to support a globe, two cylindrical shells one of which is slidably mounted on the other, and an electrical socket, a plurality of flanged metal pieces attached to the upper cylindrical shell, said yoke being attached to 95 the upper flanges and said socket being attached to the lower flanges of said pieces.

99 5. In a lighting fixture, the combination of two cylindrical shells, one of which is slidably mounted on the other, one of said cylindrical shells being provided with a plurality of bayonet pins and the other shell being provided with slots to engage the bayonet pins and adapted to permit adjustment and to clamp the adjusted shell in either of 100 two positions, an electrical socket, a plurality of flanged metal pieces attached to the upper cylindrical shell, a yoke consisting of a single piece of material having its ends turned outward and adapted to support a globe, said 105 yoke being attached to the upper flanges of said flanged metal pieces and said socket being attached to the lower flanges of said flanged metal pieces.

110 6. In a lighting fixture, the combination of two cylindrical shells one of which is slidably mounted on the other, one of said cylindrical shells being provided with a plurality of bayonet pins and the other shell being provided with slots to engage the bayonet pins and adapted to allow relative adjustment and clamping of the two shells, an electrical socket, a plurality of flanged metal pieces attached to the upper cylindrical shell, a yoke consisting of a single piece of material 115 having its ends turned outward and adapted to support a globe, said yoke being attached to the upper flanges and said socket being attached to the lower flanges of said pieces, and adjustable means comprising a metal bar 120 125 130

or strip adapted to be fastened to a ceiling and adapted to have the whole unit mounted thereon by screws passing through said adjustable means and the upper cylindrical shell.

7. In a lighting fixture, the combination of two cylindrical shells, one of which is slidably mounted on the other, cooperating means on the shells for permitting adjustment and to clamp the adjusted shell in one of a plurality of positions, an electrical socket, a plurality of flanged metal pieces attached to the upper cylindrical shell, a yoke having out-turned ends and adapted to support a globe, said yoke being attached to the upper flanges of said flanged metal pieces, and said socket being attached to the lower flanges of said flanged metal pieces.

In testimony whereof, I have hereunto subscribed my name this 24th day of November, 1930.

FREDERIC C. WINKLER.
